UNITED STATES PATENT OFFICE

SAMUEL GORMLY, OF CORAOPOLIS, PENNSYLVANIA, ASSIGNOR TO FORSTER MANUFACTURING COMPANY, A CORPORATION OF PENNSYLVANIA

GAS CANNON

Application filed November 6, 1929. Serial No. 405,183.

This invention relates to toy cannons, and particularly to cannons employing carbide or other similar material as a gas generating medium.

5 Gas cannons have been constructed heretofore for amusement purposes, carbide being employed as a gas generating medium. The cannons, as heretofore constructed, include an explosion chamber and a well for water, the 10 well being located in the bottom of the explosion chamber. Gas is generated by inserting carbide into the explosion chamber and depositing it in the well. When the gas has been liberated and mixed with the air in 15 the explosion chamber the gaseous mixture is ignited.

Cannons of this type are not self scavenging, consequently the products of combustion resulting from the explosion remain in the 20 explosion chamber. If the products of combustion are not blown out prior to the introduction of a new charge of gas, there will not be a sufficient amount of pure air in the explosion chamber to produce a proper explosive mixture. The result is that the mixture 25 of air and gas will not either explode at all or if it does explode, the report will be very muffled.

Cannons of the prior art type referred to 30 above do not lend themselves to rapid firing and are, therefore, objectionable in this respect. These cannons are also objectionable in that the products of combustion resulting from the explosion form deposits in the explosion chamber and further, the carbide 35 solidifies in the well or water basin. Consequently, after cannons of this character have been fired a few times, the deposits from the products of combustion and the carbide so 40 materially reduce the dimensions or the volume of the explosion chamber and the water container or basin that the cannons are rendered substantially or practically inoperative.

45 An object of the invention is to provide for completely and positively scavenging the explosion chamber of a gas cannon adapted to employ carbide or other similar material as the gas liberating medium.

50 Another object of the invention is to pro-

vide for positively scavenging and charging the explosion chamber.

A still further object of the invention is to 55 positively establish a uniform explosive mixture for a gas cannon.

A further object of the invention is to provide a gas cannon of the character set forth above that shall admit of rapid firing.

A still further object of the invention is to 60 provide for automatically admitting measured quantities of carbide or other gas liberating material to the gas generating chamber simultaneously with the scavenging and charging of the explosion chamber.

A still further object of the invention is to 65 provide an improved gas cannon of the character set forth above.

70 And a still further object of the invention is to provide a toy gas cannon that shall be simple in construction, efficient in operation, low in cost and that shall admit of firing as rapidly as it is physically possible for the operator to manipulate the cannon.

75 Other objects of the invention will, in part, be obvious to those skilled in the art and will, in part, be apparent from the following description taken in conjunction with the accompanying drawings in which:

80 Figure 1 is a view in perspective of a gas cannon arranged and constructed in accordance with the invention;

Fig. 2 is a view in vertical section taken on line II—II of Fig. 1;

85 Fig. 3 is a view in side elevation of a piston valve or movable partition embodied in the explosion chamber of the gas cannon shown in Figs. 1 and 2;

Fig. 4 is a front view in elevation of the 90 device shown in Fig. 3;

Fig. 5 is a view in rear elevation of the 95 device shown in Figs. 3 and 4; and

Fig. 6 is a view in perspective of a removable water container embodied in the gas generating chamber of the cannon, the water container being mounted on a rod that extends through the gas generating chamber and into the explosion chamber for actuating the piston valve or movable partition shown in Figs. 3, 4 and 5.

100 Throughout the drawings and the speci-

fication, like characters of reference indicate like parts.

With reference to Fig. 1 of the drawings, a toy cannon 1 is shown that comprises a cylinder 2 mounted on a base 3 and a muzzle or barrel 4 detachably mounted at one end of the cylinder 2. A hopper or storage device 5 for carbide or gas liberating material is mounted on the top of the cylinder 2.

10 In Fig. 2 of the drawings, a stationary partition 6 is shown that divides the cylinder 2 into chambers 7 and 8, the chamber 7 being the explosion chamber and the chamber 8 comprises the gas generator or the gas generating chamber. In order that gas may flow from the gas generator or gas generating chamber 8 into the explosion chamber 7, an aperture 9 is provided in the partition 6 that is controlled by a valve 10 loosely mounted on a pin 11 that extends through the valve and the top of the partition 6. The valve 10 is preferably of the flapper type as shown, although other types of valve suitable for the purpose may be employed.

15 In order that gas may be generated in the gas generator or gas generating chamber 8, a removable water container 12 is provided. As shown in Fig. 6 the removable water container 12 is of substantially cylindrical form and open at the top, as indicated at 20 13. A hollow sleeve 14 extends between side walls 16 and 17 of the container and is rigidly secured thereto. Openings in the side walls 16 and 17 disposed in alignment with 25 the hollow sleeve 14 provide an unrestricted passageway for a member or piston rod 18. The purpose of the member or piston rod 18 will be subsequently set forth in detail.

30 In order that predetermined or measured quantities of carbide may be transferred from the storage or hopper 5 into the water container 12, a measuring device 21 is provided. The measuring device 21 comprises a slide 22 that is movably disposed in a 35 housing 23 mounted on the top of the cylinder 2 at the gas chamber end thereof. The housing 23 is provided with an opening 25 that communicates with the gas chamber 8 immediately above the open top 13 in the 40 water container 12. As shown, the slide 22 is provided with an opening or aperture 26 that registers with the opening 25 when the slide 22 is in the full line position as indicated in Fig. 2 of the drawings. In order 45 to insure that the apertures 25 and 26 will be in register or alignment when the slide 22 is in the full line position indicated in Fig. 2, a stop 27 is mounted on top of the 50 cylinder 2.

55 In practice the thickness of the slide 22 and the diameter of the aperture 26 is such that the aperture will receive a measured or predetermined quantity of carbide or other gas liberating material when the slide is

60 moved to the right to the position indicated in broken lines.

Upon movement of the slide 22 to the position indicated in broken lines, the aperture 26 is in register with the opening 29 in the bottom of the hopper or storage device 5. In this position carbide enters the aperture 26 and fills it. Upon movement of the slide 22 to the left in the position indicated in full lines, the carbide drops through the 70 aperture 25 into the water of the container 12. Gas is then formed by the reaction between the water and the carbide, a well known characteristic.

75 In order that the gas generated in the gas generating chamber 8 may be transferred to the explosion chamber 7 a movable partition or piston valve 31 is provided and is mounted on one end of the member or piston rod 18. The piston rod 18, as shown in Fig. 80 2, extends from the movable partition or piston valve 31 through the partition 6, the sleeve 14 and a detachable closure member 32 mounted on the right-hand end of the cylinder 2 and terminates in a handle or gripping member 33.

85 The movable partition or piston valve 31 comprises two rings 34 and 35, a packing ring 36 disposed between the rings 34 and 35 and a circular metal plate 37. The disc 90 37 is provided with a plurality of apertures 38 arranged to permit the flow of gas therethrough when the piston valve is moved to the right as viewed from Fig. 2.

95 The piston valve 31 includes also a valve member 38' loosely mounted on pins 39 that are attached to the circular plate 37 in any suitable manner.

100 If the piston valve 31 is moved quickly to the left, as viewed from Fig. 2, the valve member 38 moves into contact with the ring 37 thereby closing the apertures 38.

105 Assuming that gas has formed in the gas generating chamber 8 by reason of a predetermined or measured quantity of carbide 110 having been charged or delivered to the water in the container 12, the handle 33 is gripped by the operator and pulled to the right. The handle 33 is then pushed forward quickly 115 thereby decreasing the pressure between the partition 6 and the side 41 of the movable partition or piston valve 31. Since the pressure is decreased, the valve 10 opens to permit the flow or transfer of gas from the chamber 8 into the explosion chamber 7. The next step 120 in the operation of the device consists in moving the handle 33 quickly to the right whereby the valve member 38' is actuated to the position shown in Fig. 3 of the drawings and the gas is transferred from the side 41 of the 125 valve 31 through the apertures 38 in the movable partition or piston valve to the left side or face 43 of the movable partition or piston valve.

130 The gas having been transferred to the ex-

5 plosion chamber 7, it may be ignited by means of a spark admitted through a touch hole 44 in the top of the cylinder 2 that communicates with the explosion chamber 7. When the explosion has taken place, the handle 33 is pushed quickly to the left and the gas or products of combustion is scavenged or expelled from the explosion chamber 7 through the muzzle 4 to the atmosphere.

10 In order to facilitate scavenging of the explosion chamber and also to improve the detonation of the explosions in the explosion chamber, a baffle 45 is provided. The baffle 45 may be integral with muzzle 4 and positioned 15 adjacent to the scavenging end of the explosion chamber 7 as shown in Fig. 2 of the drawings. The baffle 45 is provided with an aperture 45' the diameter of which is substantially smaller than the diameter of the explosion 20 chamber 7 for best results concerning the scavenging and detonating characteristics of the cannon.

25 Since the aperture 45 is of smaller diameter than the cylinder 2, a restricted passage-way is provided between the explosion chamber and the muzzle 4. Therefore, when the gas is scavenged, upon movement of the piston valve 31 towards the forward or scavenging end of the explosion chamber, a relatively 30 high velocity is imparted to the exploded gas thereby insuring positive and complete scavenging of the gases. The baffle also acts as a barrier against the reentrance of the exploded gases that may remain in the muzzle 35 4, to the explosion chamber upon the return or rearward stroke of the piston valve 31.

35 Since the gas generated by the reaction between the carbide or other gas liberating material and the water in the container 12 is not in itself explosive, provision must be 40 made for creating the proper mixture of air and gas when the gas has been transferred to the explosion chamber 7. In order to insure that the gas, when it has been transferred to the explosion chamber 7 will be mixed with 45 the proper amount of air to support combustion, a valve 46 is provided in the bottom of the explosion chamber 7 and adjacent to the partition 6. The valve 46 may be of the disc type and is disposed to control the flow of air 50 from the atmosphere through an opening 47 in the bottom of the cylinder 2.

55 When an explosion has taken place in the explosion chamber 7, the piston valve or movable partition 31 is moved quickly to the position shown in Fig. 2. In response to movement of the valve or partition to the position shown in Fig. 2, the pressure in the explosion chamber 7 is reduced to a value below atmospheric. Therefore, the valve 36 is raised to thereby permit air to enter the explosion chamber 7. The air mixes with the gas that is drawn into the explosion chamber 7 in response to the forward movement of the movable partition or piston valve 31. Upon the

5 return of the piston valve to the right hand end of the explosion chamber 7 (that is to the position which the valve would occupy when the handle 33 is in the position indicated in broken lines), and if a spark is introduced 76 through the touch hole 44, the gas is exploded.

To secure the desired operation of the toy cannon illustrated in the drawings, and to render it possible to explode gas in the chamber 7 in response to each scavenging and 75 charging operation effected by the movable partition or piston valve 31, a measured quantity of carbide must be transferred from the storage device 5 or hopper to the water container 12. In order to insure that a measured 80 quantity of the carbide will be introduced or transferred to the water container 12 automatically with each complete stroke of the handle 33, a post or arm 47 is mounted on the member or piston rod 18 adjacent to the forward end of the handle 33. A link 48 of substantially U-shape is secured to the upper end of the arm or member 47 and is disposed to pull the slide 22 to the position indicated in broken lines in Fig. 2 of the drawings when the handle 33 is actuated to the position indicated in broken lines. The arm or member 47 is so arranged that it pushes the slide 22 to the position indicated in full lines in Figs. 1 and 2 of the drawings in response to the 85 forward stroke of the piston rod or member 18. The reciprocating motion of the slide 22 is effected with each complete stroke of the piston valve 31.

90 Since the slide 22 of the measuring device 21 is operated simultaneously with the operation of the piston valve or partition 31, a measured quantity of carbide or gas liberating material is transferred to the water container for each explosive mixture. The explosive mixture comprises the gas liberated from the carbide and the air in the explosion chamber. Since the measuring device 21 and the piston valve 31 are operated simultaneously, the cannon may be fired as rapidly 95 as it is physically possible to manipulate the handle 43 backwards and forwards to the position indicated in full and broken lines and, at the same time, introduce a spark through the touch hole 44.

100 As shown in Figs. 1 and 2 of the drawings, the muzzle 4 is provided with an annular flange 49 that is disposed to fit over the end of the cylinder 2 and to be secured thereto by a bayonet joint. The bayonet joint includes a 105 plurality of spaced slots 50 that terminate in an offset 51 that cooperates with dowels or pins 52 secured to the end of the cylinder 2. In order to remove the muzzle 4 from the cylinder 2 it is turned in a direction indicated by the arrow at 54 until the slots 50 are in register with the pins or dowels 52. The muzzle 4 may then be pulled off the end of the cylinder 2. To replace or reassemble the 110 muzzle 4 on the cylinder 2, the reverse oper- 115

ation takes place and the muzzle is locked in position as shown in Figs. 1 and 2.

As the muzzle 4 is removable, the explosion chamber 7 may be cleansed of the products of combustion which result from the explosion of the mixture of carbide gas and air. The closure member 32 is similar in construction to the annular flange 49 and is removable in the same manner. Since the closure member 32 is removable, the water container 32 may be removed from the gas generating chamber 8 for cleaning purposes.

While various modifications and changes may be made in the cannon illustrated and described without departing from the spirit and the scope of the invention, it is to be understood that only such limitations shall be placed on the invention as are imposed by the prior art and the appended claims.

20. What I claim as new and desire to secure by Letters Patent is:

1. A toy cannon comprising an explosion chamber, a gas generating chamber including a water container, a piston valve in the explosion chamber, means for moving the piston valve longitudinally of the explosion chamber, a storage device for gas liberating material, a measuring device and means for operating the measuring device in response to movement of the piston valve for transferring a measured quantity of gas liberating material from the storage device to the water container.

2. A gas cannon comprising an explosion chamber, a gas generator including a water receptacle, means for scavenging and charging the explosion chamber, a storage device for gas liberating material associated with the gas generator, a measuring device, and means for operating the measuring device in response to the operation of the scavenging and charging means whereby a measured quantity of gas liberating material is delivered to the water container.

3. A gas cannon comprising an explosion chamber, a gas generator including a water receptacle, means for scavenging the explosion chamber, and means for charging the water receptacle with a measured quantity of gas liberating material in response to the operation of the scavenging means.

4. A gas cannon comprising an explosion chamber, a piston valve movably disposed within the chamber, an opening in the bottom of the explosion chamber communicating with the atmosphere and a valve for controlling said opening.

5. A toy cannon comprising an explosion chamber, a gas generator including a water receptacle, a valve for controlling communication between said generator and chamber, a partition movably disposed in the explosion chamber, a storage device for gas liberating material associated with said gas generator, a measuring device for transfer-

ring measured quantities of gas liberating material from the storage device to the water container, means for moving the movable partition longitudinally of the explosion chamber, and means for operating the measuring device in response to movement of the movable partition in the explosion chamber.

6. A toy cannon comprising an explosion chamber, a gas generating chamber, a valve for controlling communication between said chambers, a water container disposed in the gas generating chamber, a partition movably disposed in the explosion chamber, a magazine for gas liberating material associated with said gas generating chamber, a measuring device for transferring measured quantities of gas liberating material from the magazine to the water container, means for moving the movable partition longitudinally of the explosion chamber and means for operating the measuring device in response to movement of the partition movably disposed in the explosion chamber.

7. A toy cannon comprising an explosion chamber, a gas generating chamber, a valve for controlling communication between said chambers, a water container disposed in the gas generating chamber, a partition movably disposed in the explosion chamber, a storage device for gas liberating material associated with said gas generating chamber, a measuring device for transferring measured quantities of gas liberating material from the storage device to the water container, a rod extending into the explosion chamber and connected to the movable partition for moving the same longitudinally of the explosion chamber and means for operating the measuring device in response to movement of the partition movably disposed in the explosion chamber.

8. A toy cannon comprising an explosion chamber, a gas generating chamber, a valve for controlling communication between said chambers, a water container disposed in the gas generating chamber, a partition movably disposed in the explosion chamber, a storage device for gas liberating material associated with said gas generating chamber, a measuring device for transferring measured quantities of gas liberating material from the storage device to the water container, a rod extending into the explosion chamber and connected to the movable partition for moving the same longitudinally of the explosion chamber, a post mounted on said rod and extending at an angle therefrom, said post being disposed to actuate the measuring device in one direction and a link extending from said post disposed to operate the measuring device in another direction in response to movement of the partition movably disposed in the explosion chamber.

9. A gas cannon comprising a cylinder having an explosion chamber and a gas gen-

erating chamber and a valve for controlling admission of air from the atmosphere to the explosion chamber in response to a decrease in pressure in the explosion chamber below atmospheric.

5 10. A gas cannon comprising a cylinder having an explosion chamber and a gas generating chamber, means for scavenging the explosion chamber and transferring gas from the gas generating chamber to the explosion chamber.

10 15. A gas cannon comprising a cylinder, a stationary partition disposed in said cylinder between the ends thereof, a gas generator in the cylinder on one side of said stationary partition, a movable partition on the other side of said stationary partition, and a valve for controlling the transfer of gas from the generator through the stationary partition.

15 20. A gas cannon comprising a cylinder, a stationary partition disposed in said cylinder between the ends thereof, a gas generator in the cylinder on one side of said stationary partition, a movable partition on the other side of said stationary partition, a valve in the movable partition, and a valve for controlling the transfer of gas from the generator through the stationary partition.

20 25. A gas cannon comprising a cylinder, a stationary partition disposed in said cylinder between the ends thereof, a gas generator in the cylinder on one side of said stationary partition, a movable partition on the other side of said stationary partition, and a valve for controlling the admission of air into that part of the cylinder in which the movable partition is disposed in response to movement of the movable partition away from the stationary partition.

30 35. In testimony whereof, I have hereunto subscribed my name this 26th day of October, 1929.

SAMUEL GORMLY.
